DITCH-DIGGING MACHINE.

1,385,674.

Specification of Letters Patent. Patented Mar. 30, 1920.

Application filed November 14, 1917. Serial No. 201,917.

To all whom it may concern:

Be it known that I, JOHN ENGEN, a subject of the King of Norway, residing at Byneset, Bodsberg, in the Kingdom of Norway, have invented certain new and useful Improvements in Ditch-Digging Machines; and I do hereby declare the following to be a full, clear, and exact description of the invention, such as will enable others skilled 10 in the art to which it appertains to make and use the same, reference being had to the accompanying drawings, and to letters or figures of reference marked thereon, which form a part of this specification.

15 This invention relates to ditch digging machines of the kind where a cutting iron digs up a layer of earth the thickness of which is regulated by means of an adjustable support at the front end of the apparatus, and where the earth loosened by the cutting iron is conveyed to the surface by means of an inclined conveyer located behind the cutting iron.

20 The invention relates to the driving arrangement for this conveyer and consists in arranging the conveyer in direct engagement with teeth at the circumference of the wheel or wheels carrying the apparatus.

25 A feature of this invention is the provision of a frame for carrying the conveyer and the digging element which is carried by a single ground roller so as to have a normal tendency to tilt upwardly away from the ground to permit the machine to be easily 30 turned and to permit the digging element to pass over obstructions in its path without being damaged thereby. The frame has a platform for receiving a weight, by means of which the digging element is held to the 35 ground. Preferably the operator constitutes this weight and the platform is in a position where the operator may readily step on and off the platform to control the 40 digging element.

45 Another feature of this invention is the provision of a trench or ditch digging machine which will be capable of digging relatively deep trenches. For the purpose the ground roller is adapted to travel along the 50 bottom of the trench and the digging element is made wider than the roller, the frame and the conveyer, so as to dig a trench of sufficient width to permit the roller, the

frame and the conveyer to freely pass through the trench.

55 The drawing illustrates diagrammatically a form of the invention.

The digging element is in the form of a cutting iron 1, which cuts into the earth at a depth regulated by an adjustable guide or 60 shoe 2, which slides along the surface in front of cutting iron 1.

65 Behind the cutting iron 1 is located the conveyer 3 mounted on rollers 4, 5. Said conveyer is formed as a chain and on its underside is engaged by teeth 6 on wheel 7 carrying the digging apparatus. During the forward movement of the digging apparatus the upper side of the conveyer will move backward with the same velocity with 70 which the apparatus moves forward and thus will remove the earth cut up by iron 1 without any change of speed. It will be seen that the earth dug up will practically perform only a vertical movement with regard 75 to the surroundings, and this evidently represents the most economic speed for the conveying chain. At the same time the driving arrangement for the conveyer is the simplest possible requiring no other driving wheel 80 than the support wheel of the machine.

85 The cutting iron 1 is secured to the forward end of the rectangular frame 8 which is provided with depending arms 9 about midway of its length. The arms 9 form 90 bearings for the shaft 10 of the single ground roller 7, and about which the frame may swing. The frame 8 has a normal tendency to tilt upwardly away from the ground, thus tending to raise the cutting iron 1 away 95 from the ground. For the purpose of maintaining the cutting iron 1 in its working position, as shown in the drawing, the frame 8 is provided with a platform 11 which is secured thereto and which is located directly above the cutting iron. The platform is adapted to receive a weight to overcome the normal tendency of the frame to tilt upwardly. Preferably the operator stands 100 on the platform for this purpose. The platform is so positioned that the operator may conveniently step off or on the platform. In practice, the operator on observing an obstruction in the path of the cutting iron, steps off the platform, whereupon the frame 105 tilts upwardly and the cutting iron passes

over the obstruction without being damaged or arrested thereby.

The cutting iron 1 is wider than the ground wheel, the frame or the conveyer and thus digs a trench of sufficient width to permit said parts to freely travel therein. This permits the machine to dig a relatively deep trench.

A chute 12 receives the loose soil from the 10 conveyer and deposits the same at the side of the trench.

The machine is drawn through the trench by a chain 13 or other suitable draft means.

Claims:

15 1. In a trench digging machine, the combination of a rectangular frame which in normal working position inclines upwardly and rearwardly from the digging end thereof; a digging element carried by the digging 20 end of the frame; a single ground roller carrying said frame at a point substantially midway of the length of the frame on which said frame is tilttable and so arranged with respect to the weight of the frame that 25 the digging end of the frame has a normal tendency to tilt upwardly away from the ground; a platform on the frame directly above the digging element adapted to receive a weight for holding the digging element to the ground; and an adjustable guide 30 carried by the frame and extending in front

of the digging element adapted to control the depth of the cut made by the digging element.

2. In a trench digging machine adapted 35 to be drawn along the ground, the combination of a rectangular frame which in normal working position inclines upwardly and rearwardly from the digging end thereof; a digging element carried by the digging 40 end of the frame; a single ground roller carrying said frame at a point substantially midway of the length thereof on which the frame is tilttable and so arranged with respect to the weight thereof that the digging 45 end of the frame has a normal tendency to tilt upward away from the ground; a platform on said frame above the digging end thereof, said platform being so arranged that the operator may stand thereon to hold 50 the digging element to the ground or move off said platform to permit the digging element to swing upwardly to pass an obstacle without engaging therewith.

In testimony that I claim the foregoing 55 as my invention I have signed my name in presence of two subscribing witnesses.

JOHN ENGEN.
